UNITED STATES PATENT OFFICE.

HERBERT M. KNIGHT, OF MONTCLAIR, NEW JERSEY.

PAVEMENT.

Application filed August 10, 1921. Serial No. 491,227.

This invention relates to pavements, and has special reference to pavements composed in part of pre-cast concrete units.

One of the objects of the invention is to provide a pavement built up of units, any one or several of which may subsequently be removed and replaced. Another object of the invention is to provide a pavement, parts of which may be removed for the purpose of permitting underground work to be performed, while the remainder of the pavement remains intact, permitting of continuous use by traffic. Another object of the invention is to provide a pavement built up of pre-cast units severally supported upon and removably attached to other units. Another object of the invention is to provide a pavement built up of pre-cast units and covered with a wearing coat above the said pre-cast units. Another object of the invention is to provide a pavement built up of pre-cast units with means for filling void spaces which may exist beneath said pavement. Another object of the invention is to provide a pavement, one portion of which consists of pre-cast slabs resting upon and removably attached to sills supporting said slabs. A further object of the invention is to produce a unit type of pavement in which the several units comprising similar parts shall be interchangeable. Still another object of the invention is to provide a pavement with ducts therein for the passage of heat for the melting of ice and snow from the surface of the said pavement. Another object of the invention is to provide a pavement, the pre-cast slabs of which are supported in part by the curbing along said pavement. Other objects of the invention will appear from the following description and from the accompanying drawings.

The accompanying drawings, Figures 1 to 13 inclusive, are illustrative of the invention, and indicate the usual and preferred embodiment thereof. They are however illustrative only and are not to be considered as inclusive of all types in which the invention may be embodied, nor as exclusive of other types than that indicated.

I illustrate my invention by the accompanying drawings in which Fig. 1 is a cross-section of the pavement on the line 1—1 of Fig. 2; Fig. 2 is a plan view of a pavement, parts of said plan showing the wearing coat removed; Fig. 3 is a longitudinal section of a slab or unit employed in the said pavement; Fig. 4 is a section at the curb-line and

Fig. 5 a section at an intermediate sill; Fig. 6 is an elevation of the hook-bolt used for removably connecting the slabs to the curbs and sills; Fig. 7 is a section of such a hook-bolt on the line 7—7 of Fig. 6; Fig. 8 is a section of the bolt on the line 8—8 of Fig. 6; Fig. 9 is a plan of a portion of a pavement at a sill with the wearing coat removed; Fig. 10 is a plan view of a curb; Fig. 11 is an elevation of a sill and Fig. 12 a plan view of such a sill. Fig. 13 is a cross-section of a sill and pavement showing their application in the support and maintenance of a rail.

Referring to the drawings in which similar figures refer to similar parts. 1 is a pre-cast slab partially supported by a curb 2 having a shoulder 3 positioned to support said slab. The slab may also be supported in whole or in part by a sill 4 having a shoulder 5 at the upper part thereof. Hook-bolts 6 pass through bolt holes 7 in said slab, said bolts removably engaging said shoulders 3 and 5. The bolt holes 7 have an elongated opening 8 in the bottom face of the slab and are provided with a shoulder 9 for the purpose of engaging a washer 10 which is forced against the shoulder 9 by a nut 11 which engages a screw thread on the shank of the hook-bolt. The hook-bolt 6 has an extension 13 with an upper face 14 flattened to make superficial contact with the bottom of the shoulders 3 and 5. A hole 15 for the purpose of washing or grouting material beneath the pavement after the placing of the slabs and before the laying of the wearing coat, and also as a means of handling the slabs during the process of insertion or removal, is provided. Plugs 16 of easily removable material, amorphously inserted, fill the bolt holes 7 and grouting holes 15, protecting the ends of the bolts and permitting easy removal for the purpose of withdrawing bolts and removing and handling slabs. A wearing coat 17 covers the slabs and fills the joints between the several slabs and between the slabs and curbs. Ducts 18 for the purpose of conveying heat, are formed in the body of the slabs, the ducts of juxtaposed slabs being in linear alinement. A boss 19 is formed upon the bottom of the sill 4 and rebates 20 on the inner faces thereof. Bolt holes 21 pass through the webs of the sills and bolts 22 are inserted in said bolt holes and securely fasten the duplicate parts of the sills together. Clips 23 are shown, positioned in the rebates 20 having bolt holes 24

therein through which the bolts 22 pass. The upper ends of said clips 23 are provided with an offset 25 adapted to engage the base of a rail 26 and to be secured thereto by means of a wedge 27. The upper flange of the sill 4 has a depression 28 adapted to receive the base of the rail 26, and a chase 29 adapted to receive the offset 25 of the clip 23. The chase 29 has an oblique back 30 permitting latitude of movement of the clip 23. A shoulder 31 is formed upon the back of the curb 2, supporting the sidewalk slab 32. Sewers 33, conduits 34, water pipes 36 and gas pipes 37 are indicated as located beneath the said pavement.

In the construction of city pavements, as usually performed, a foundation of concrete is laid upon the sub-grade, either with or without consolidation, and a wearing coat 20 of brick, asphalt, or other resistant or resilient material is superimposed thereupon. Subsequently excavations are made through this foundation and wearing material, in order to reach and repair existing sub-surface pipes, or for the purpose of introducing new ones. In the process of such excavation all of the foundation and other pavement material removed is broken up and destroyed, and an area largely in excess of 25 that required is injured, such destruction and injury entailing great waste and heavy costs for restoration. In the pavement herein illustrated, pre-cast slabs, usually of concrete, are supported upon curbs and longitudinal sills and removably attached to said curbs and sills by means of hook-bolts, which, while holding the slabs rigidly in position while the pavement is in service, are quickly and easily removable, allowing the 40 slab, with its superimposed wearing surface to be removed from the section of the roadway, beneath which it is desired to make excavation. All of the removed paving material, being by this process preserved, is easily and quickly returned to position and the pavement immediately restored. The only portions of the wearing surface destroyed are the portions along the edges of the slabs, the restoration of which 45 is a small and inexpensive matter. The hook-bolt being of the illustrated form is easily inserted in the bolt hole through the slab, the elongated bottom of the said bolt hole permitting of the introduction of the 50 hook-bolt so that the hook is parallel to the curb or sill, when, upon such introduction, the hook is turned through an angle of 90 degrees and the flattened face of the hook brought into contact with the lower face of 55 the shoulder on the curb or sill and fastened thereto by means of the nut resting upon the washer which is in contact with the shoulder within the bolt hole. As the bolt hole is filled with some easily removable material which is easily removable and

which will not clog the threads of the bolt, in case it is desired to remove a slab or a section of pavement for repair or other purpose, the hook-bolts are easily and quickly removed by loosening the nut, turning the hook of the bolt so that it will be in line with the major axis of the elongated aperture and withdrawing it from the pavement. The slabs are therewith freed from the sills or curbs and can be lifted, and subsequently 75 replaced, it being possible to re-insert and fasten the same bolts in the same as the initial manner.

One of the defects of a slab type of pavement is the possibility of cavities being left, or later appearing, beneath the pavement. While a sub-grade can be so carefully dressed as to make the presence of such cavities both small or remote, provision against their arising and becoming a dangerous 80 menace to the life or safety of the pavement are desirable. For the purpose of preventing the presence of such cavities after the pavement shall have been laid or replaced, grouting holes are provided in each of the 85 slabs or units making up the pavement, through which earth or other material may be washed or grouted beneath the slabs, in advance of the laying of the wearing coat. By such washing or grouting all voids beneath the pavement are filled, and a pavement resting firmly upon the soil over its 90 entire area is secured.

The slabs rest upon curbs and also upon longitudinal sills, the latter, for greater 100 ease in manufacture and in handling, being in multiple, the said multiple sill units being assembled in relatively reversed position in the pavement and breaking joint with each other. They are connected together by bolts. Such multiplicity of members and such breaking of joints produces a rigid structure and prevents irregular settlement of the pavement under traffic. The superficial pre-cast slabs supported by the curbs and 105 sills, likewise are staggered so as to give a maximum of strength and to insure a regularity of surface. The sills are rebated on their backs, the purpose of such rebating being to provide a slot or space for the insertion of means, such as the tie or clip shown, for fastening a rail, or other superficial body or construction, to the sills or pavement.

One of the greatest drawbacks to the use 110 of a smooth pavement in city streets, where frost conditions are liable to exist, in the colder months, is the formation of a thin coating of ice thereon, making the pavement very slippery and dangerous to either 115 horse drawn or motor traffic. Such slipperiness can be prevented if the surface of the pavement is maintained at a degree or two above freezing. Again, except for excessively heavy snowfalls, the removal of the 120

snow can be greatly facilitated, if not entirely performed, if the pavement is kept slightly warm, sufficiently to melt the snow as it falls. For the purpose of securing this 5 result, ducts are shown as having been formed in the body of the slabs during the casting thereof, so alined as to make a continuous passage or series of passages under and through the pavement, such ducts leading 10 to some central heating plant, from which hot air, steam or hot water is circulated for the purpose of heating the pavement to a temperature slightly above freezing. 15 The wearing surface, being laid in situ, and after the slabs have been attached to the curbs and sills, fills all cracks and other divisional lines between the slabs and between the slabs and curbs, and makes there- 20 by a continuous and unbroken paving surface.

What I claim is:—

1. In a pavement, a pre-cast slab, a sill supporting said slab, said sill being composed 25 of a multiple of units, downwardly directed shoulders on the upper portion of said units, flanges on the lower portion of said units, fastening means joining said units and bolts engaging under said shoulders on said sills and removably attaching said slabs and said sills.

2. In a pavement, a pre-cast slab, a sill supporting said slab, said sill being composed of a multiple of units having rebated backs, 35 downwardly facing shoulders on the upper portion of said units oppositely disposed to said rebated backs, flanges on the lower portion of said units, fastening means joining said units and bolts passing through bolt-holes in said slabs and engaging under said shoulders on said sills and removably attaching said slabs and said sills.

3. In a pavement, a pre-cast slab, sills supporting said slab, said sills being composed 45 of a multiple of units, shoulders on the upper portion of said units, flanges on the lower portion of said units, fastening means joining said units, bolts engaging said shoulders on said sills and removably attaching said slabs and said sills and a superficial wearing coat upon said slabs.

4. In a pavement, a pre-cast slab, sills supporting said slab, said sills being composed of a multiple of units, rebated backs to said units, shoulders on the upper portion of said units oppositely disposed to said rebated backs, flanges on the lower portion of said units, fastening means joining said units, bolts passing through bolt-holes in said slabs and engaging said shoulders on said sills and removably attaching said slabs and said sills and a superficial wearing coat upon said slabs.

5. In a pavement, a pre-cast slab, sills supporting said slab, said sills being composed

of a multiple of units, downwardly directed shoulders on the upper portion of said units, flanges on the lower portion of said units, fastening means joining said units, bolts engaging under said shoulders on said sills and removably attaching said slabs and said sills and grouting holes in said slabs. 70

6. In a pavement, a pre-cast slab, sills supporting said slab, said sills being composed of a multiple of units, rebated backs to said units, shoulders on the upper portion of said units oppositely disposed to said rebated backs, flanges on the lower portion of said units, fastening means joining said units, bolts passing through bolt-holes in said slabs and engaging said shoulders on said sills and removably attaching said slabs and said sills and grouting holes in said slabs. 75

7. In a pavement, pre-cast slabs, a plurality of sills common to a plurality of slabs 80 and supporting the same, said sills being composed of a multiple of units, shoulders on the upper portion of said units, flanges on the lower portion of said units, fastening means joining said units, bolts engaging said shoulders on said sills and removably attaching said slabs and said sills and grouting holes in said slabs. 85

90

8. In a pavement, a plurality of juxtaposed alined pre-cast slabs, a plurality of sills common to a plurality of slabs and interposed under the marginal alined edges of said slabs, said sills being composed of a multiple of units, shoulders on the upper portion of said units, flanges on the lower portion of said units, fastening means joining said units, bolts engaging said shoulders on said sills and removably attaching said slabs and said sills and ducts in said slabs, said ducts being alined in successive slabs and held in alinement by the attaching of said slabs to the common sills. 95

100

9. In a pavement, a pre-cast slab, sills supporting said slab, said sills being composed of a multiple of units, rebated backs to said units, shoulders on the upper portion of said units oppositely disposed to said rebated backs, flanges on the lower portion of said units, fastening means joining said units, bolts passing through bolt-holes in said slabs and engaging said shoulders on said sills and removably attaching said slabs and said sills 115 and ducts in said slabs.

120

10. In a pavement, the combination of pre-cast slabs, curbs and sills supporting said slabs, bolts passing through bolt-holes in said slabs and engaging shoulders on said curbs and sills, and removably attaching said slabs to said curbs and sills, grouting holes in said slabs, ducts in said slabs and a superficial wearing coat thereon. 125

11. In a pavement, the combination of pre-

130

cast slabs, pre-cast curbs and sills supporting said slabs, bolts passing through bolt-holes in said slabs and engaging shoulders on said pre-cast curbs and sills and removably attaching said slabs to said curbs and sills, grouting holes in said slabs, ducts in said slabs and a wearing coat superimposed upon said slabs.

12. In a pavement, a multiple of pre-cast slabs, a hook-bolt and a projecting arm to said bolt, the upper surface of which arm is flattened.

13. In a pavement, the combination of

pre-cast slabs, pre-cast curbs and pre-cast sills supporting said slabs, hook-bolts passing through shouldered bolt-holes having an elongated lower aperture, in said slabs, and engaging shoulders on said pre-cast curbs and pre-cast sills, and removably attaching said slabs to said curbs and sills, grouting holes in said slabs, ducts in said slabs and a wearing coat superimposed upon said slabs.

Signed at New York in the county of New York and State of New York this ninth day of August, A. D. 1921.

HERBERT M. KNIGHT.
